UNITED STATES PATENT OFFICE

120,034

DESIGN FOR A SEWING BASKET

Carl D. Langenbacher, Noank, Conn.

Application June 11, 1938, Serial No. 77,766

Term of patent 3½ years

To all whom it may concern:

Be it known that I, Carl D. Langenbacher, a citizen of the United States, residing in Noank, county of New London, State of Connecticut, have invented a new, original, and ornamental Design for a Sewing Basket, of which the following is a specification, reference being had to the accompanying drawing forming part thereof.

The figure is a perspective view of a sewing basket showing my design.

I claim:

The ornamental design for a sewing basket, substantially as shown.

CARL D. LANGENBACHER.
